UNITED STATES PATENT OFFICE.

JOHN R. POTTERTON, OF LYNN, MASSACHUSETTS.

FENCE.

1,115,736.

Specification of Letters Patent.

Patented Nov. 3, 1914.

Application filed November 7, 1911. Serial No. 658,959.

To all whom it may concern:

Be it known that I, JOHN R. POTTERTON, a citizen of the United States, residing at Lynn, in the county of Essex and State of Massachusetts, have invented new and useful Improvements in Fences, of which the following is a specification.

This invention relates to improvements in fences.

0 It is an object of the invention to provide an improved fence having the advantages of portability and of adaptability for use on land or in the water, in the latter case serving to exclude water, and applicable to the 5 many other uses and having the many other advantages that characterize the construction hereinafter described.

In the accompanying drawings, which illustrate embodiments of the invention, 0 Figure 1 is a plan, indicating an arrangement of the fence in a river; Fig. 2 is an elevation, showing a section across such a river; Fig. 3 is a side elevation of a portion of the fence, arranged upright, and with a 5 top binding rail added; Fig. 4 is a side elevation of a part of the same in section, showing details on a larger scale; Fig. 5 is a plan of the same, in section on the line 5-5 of Fig. 4; Fig. 6 is an end elevation of 0 a detail, in section; Fig. 7 is a side elevation similar to Fig. 4, but showing wire panels and a base especially adapted for use on land; Fig. 8 is a plan of the same, in section on the line 8-8 of Fig. 7; Fig. 9 is a plan, 5 showing a detail of Fig. 8 enlarged; Fig. 10 is a perspective view of a detail, still further enlarged; Fig. 11 is an end elevation of the fence showing style of post fastening seen in Figs. 7 and 8; Fig. 12 is a side elevation 10 of a fragment at the top of Fig. 11, enlarged, and partly in section; Fig. 13 is a plan in section on the line 13-13 of Fig. 12; and Fig. 14 is an enlarged plan of one type of post.

15 Referring to the drawings, one use and arrangement of the fence is illustrated in Fig. 1 in which it is shown as arranged in a river bed, the direction of the river being shown by the arrow, and the fence being 20 arranged to separate and inclose a portion 10 of the river bed, directing the water of the river through the channel 11 and excluding it from the portion 10 in order to 25 enable excavation or other work to be carried on. To this end, the fence provides a tight and firmly set barrier, which may be

set up with relative ease, and may be taken down and installed elsewhere.

The fence consists of a series of posts 12 and panels 13 interlocking with the posts, 60 the whole being preferably formed of sheet metal such as sheet steel, or galvanized metal. It will be understood that in the drawings the proportions and relative dimensions and distances of the parts are 65 necessarily distorted, owing to the limitations of the size of the drawing, and for the sake of clearness of illustration. The posts may be in the form shown in Fig. 5 in which, a post is seen, formed of sheet metal rolled 70 or pressed into a shape whose cross section has flat parallel sides on the opposite sides of the fence and circular socket sides in the direction of the length of the fence. The sockets are marked 14 and are adapted to 75 receive the circular bead 15 on the edge of a panel or web intervening between posts which also is preferably formed of sheet metal. Posts are made in sectional lengths, as seen clearly in Figs. 3 and 4, the bottom 80 length being a shoe 16 having a pointed end to facilitate its being driven into the soil forming the bed of the river. These sectional lengths are provided with means for being fastened to each other, which, as 85 represented, consists of screw threaded pins 17, one of which is seen in Fig. 4 arranged at one end of a section and adapted to screw into a hole 18 in the adjacent end of the next section. A sufficient number of lengths having been joined together with a shoe 16 at 90 their lower end, and having been taken to the place where the fence is to be erected in the bed of a river, the post is put in the water with its shoe resting on the bottom 95 and is then driven downward into the bed of the river, more lengths being added at the top as necessary. Preferably it is driven at somewhat of an angle from the vertical, as illustrated in Fig. 2 inclining toward the 100 side from which the water is to be excluded. A panel 13 is then pushed down edgewise, with its bead 15 in the socket 14; and then the next post 12 is pushed down at the end of this panel, with its socket 14 engaged 105 with the other bead 15 of the panel. Then another panel 13 is added, and then another post, and so on as long as desired.

If it happens that the point of a post strikes a boulder, the location of the post 110 may be changed, deflecting the location of the fence from a precise straight line

enough to avoid such boulder; for it will be observed that the socket 14, being somewhat more than a semi-circle and somewhat less than as nearly complete a circle as would be 5 possible, permits the panel and its bead to turn through a number of degrees while in the socket. The panels are put down in sections one above the other corresponding to the sectional lengths of the post. For making a corner or branch in the fence, posts are 10 provided as shown at 12' in Figs. 1 and 14 with sockets on four sides, into either of which the panels may set, thus running the panels from that post in either of the four 15 directions, with the same latitude for angular variations of direction which is provided in the other cases by the form of the socket. The sectional lengths of the posts are individually strengthened; and are at the 20 same time prepared for connection to each other, by fixing in each end of each section a solid block 19. In the block at one end of the length a screw threaded hole 18 is formed; and in the block at the other end 25 of the length a screw stud or pin 17 is set. These blocks 19 hold the sheet metal comprising the post from collapse or bending inward at each end; the peculiar shape of the sheet metal cross section makes a particularly rigid shell structure in the distance 30 between the blocks; and the filling of the sockets by the beads 15 which fit loosely therein adds further strength to the post. Preferably these beads 15 overlap somewhat 35 the junctions between sectional lengths of a post as illustrated in Fig. 4, thus combining together still more firmly the adjacent lengths of a post because the beads break joints with the post sections.

40 In order to prevent the force or lifting power of the water from loosening the fence and also in order to gain a firm setting for the part which is under earth, notwithstanding that earth is being excavated in the 45 portion 10 of the river bed, the post is preferably inclined somewhat so that its lower end projects under the water side, as illustrated in Fig. 2. By this arrangement the weight of the water counterbalances any 50 lifting effect the impact of water might exert on the fence; and the impact spends itself in throwing water up higher on the fence instead of tending to throw the fence itself up higher. The weight of the water 55 and other forces tending to dislodge the posts are resisted in part by these portions of the posts which are embedded in the earth under the river; and may in part be sustained through the aid of extension pieces 60 20, running up into the air above the top of each post, to the upper ends of which may be fastened guy ropes or wires 21 anchored in any suitable manner on the bank of the river. These poles are set in the holes 18 65 at the top of the top sections of the posts

just as additional sections of such posts would be set, to carry them higher.

Leakage of water through the fence is prevented by any suitable means, the means illustrated being strips of thin rubber 22 overlapping the cracks between the beads 15 and walls of sockets 14, Fig. 5, and strips or pads 23, protecting the horizontal joints between panels. If preferred, the sheet metal panels may be made with their upper horizontal edges formed into grooves or sockets opening upward, as illustrated in Fig. 6, in the bottom of which rubber or other suitable packing material 23 may be placed, the adjacent edge of the next higher panel fitting 75 into this socket and being seated against the rubber or other packing material. The fastening of these rubber strips 22 to the panels may be effected by occasional rivets as illustrated, or by the formation of a groove in 80 the panel, and the use of a spline which wedges one edge of the strip into the groove; or the fastening may be accomplished by any other suitable means. The grooves for holding the packing 23 may be formed between strips 24 fastened on each side of the 85 panel 13.

When the fence is to be used on land similar posts and panels may be employed, except that in this case it is obviously not necessary to have the rubber packing for the 90 cracks nor is it necessary that the panels be webs of continuous sheeting.

One form of panel which may be used if preferred is illustrated in Fig. 7 where in 100 place of a web of galvanized iron in the body of the panel, wires 25 are employed. In such case the panel has two vertical beaded edges 15 of sheet metal, as before, one arranged vertically at each end of the 105 panel and having its bead adapted to fit into the sockets 14. Top and bottom horizontal bars 26 are provided, which serve as struts. The wires 25 may be fastened at one end as indicated at 27, and as seen more in detail in 110 Figs. 9 and 10; and may be fastened at the other end to adjustable tighteners 28, as illustrated more in detail in Fig. 8. The first mentioned fastening consists of a thimble 29 passing through the two lips of 115 the rolled sheet metal which forms the bead 15 comprising the vertical edge of the panel; within the thimble 29 is the thimble 27, having a turned-in spur 30 illustrated clearly in Fig. 10, around which the wire is 120 fastened, the wire reaching it through a slot 29' in the thimble 29. At the fastening of the other end of the wire is a conical plug 28 set in the sheet metal edges in a manner corresponding to that of the thimble 29, except that, because it is conical, by pulling it 125 out endwise it is loosened and by putting it in it is tightened, that hole in the sheet metal in which one end of this plug is sealed being a little smaller than that in which the 130

other end is seated. This plug has a square head 32 which may be turned by a wrench such as a socket wrench, pressure being at the same time applied to drive it transversely into its seat. The operation of this tightener is that the wire 25, fastened to the plug, is to be tightened by twisting the plug and at the same time pressing it inward toward its seat. Friction between the plug and its seat holds it firmly at whatever degree of tightness the wire has been drawn. One of these being provided for each of the wires 25, all wires may be drawn equally tight. The rectangular wire panel illustrated in Fig. 7 thus becomes an independent unit which can be removed and inserted by itself, just like one of the web panels 13 illustrated in Fig. 4.

A convenient and novel method of fastening the fence firmly and yet removably on the ground is illustrated in Fig. 7, where the section of the post which enters the ground is sub-divided into four. A base or sill 33 is shown adapted to be attached to one of the sections 12 as if it were a sectional length of post, but its principal dimension is laterally or transversely of the fence in the horizontal direction. It extends a suitable distance to each side of the fence and rests on the ground. This sill has grooves 34 in its top adapted to receive the heads of fastening rods or shoes 35 seen best in Figs. 7 and 11 which are capable of being driven into the earth to any desired depth, for example, a foot and a half or two feet, and which may be provided with barbs to retard their movement or loosening after having been put in place. When four of these have been driven down the fence post is firmly anchored just as if the post extended down in a single shaft.

In the construction here illustrated the mass 33 rests on the surface of the ground, and may, without increasing the expenses of installation, have as wide a horizontal area or bearing on the ground as desired. The sub-division of the underground portion of the fastening holds it easily against lateral movement; while it cannot be tipped over without drawing upward all four of its fastenings at once. This last is because in tipping it would turn about one of its lateral extremities, and all of the rest of the mass would incidentally rise, the distance of rising depending on its distance from the corner about which the tipping tends to occur. When it is desired to move such a fence the panels 13 may be removed by lifting them out; and then the separate sub-divisions 35 of the underground fastening extracted singly; and the whole fence carried elsewhere and set up again. To prevent this removal by an unauthorized person a special fastening or locking device is illustrated in Fig. 3 in which is shown a rail 40 adapted

to rest upon tops of the posts 12 and to be fastened thereto, thus covering and preventing the removal of the panels 13. This rail may have any desired design, ornamental or useful, in its upper portion; and may be adapted to fit into the holes 18 in blocks 19 at the tops of the posts 12, as the sections of such posts are secured to each other. The rail may be fastened to such blocks in any suitable way; one means that may be employed being a latch 41 as illustrated, capable of being released by a key 42.

The fastening illustrated consists of two projecting spring catches, which, when inserted through the hole 18 spring apart and engage under the bottom of the block 19. These catches are pivoted as illustrated clearly in Fig. 12, so that the insertion of key 41 between the tail ends of these catches, in the position seen in Fig. 12, and the turning of the key throws the lower ends of the catches together so that they can be extracted through the hole. Removal of the rail permits the panels 13 to be removed. Another latch 43 may be provided on the panels 13, as seen in Figs. 12 and 13, whereby these panels are latched in the position on the posts. Such a spring latch may engage in one of the rolls 44, which may be provided at any desired elevation on the post.

The fence thus described is applicable to many uses other than that illustrated. The sections of post may be made in any suitable dimensions of length or of cross section and the panels likewise may be adapted to the use desired. The fence lends itself readily to use for completely inclosing a small area, such as for a chicken coop, or for a movable yard for farm stock. When so arranged, if the area included be small, a floor covering the inclosed area can be supported on the posts at the level of the bottom of the panels.

The system of anchoring the fence to the earth shown in Fig. 7 can be used under water as well as on land; and the style of panels shown in Figs. 1 to 5 can be used on land, as for example, to form a wind break or to make a billboard. Regarding the fence as a whole the invention affords a structure in which both posts and panels are made of sheet metal, the form combining strength with lightness, and being at the same time movable without damage and with relatively little effort.

I claim:—

1. The combination with a fence post adapted to receive panels on its sides, removable by lifting upward, of a piece adapted to extend laterally from the center of the post, covering the ends and preventing removal of the panels; and a lock fastening said piece on top of the post.

2. The combination with a fence post adapted to receive panels on its sides, re-

- 4
- movable by lifting upward; of a piece adapted to extend laterally from the center of the post, covering the ends of, and preventing removal of, the panels; a spring latch engagement between said piece and the interior of the post at the top; whereby the piece is normally fastened on top of the post; and a key for bending said spring to release said fastening.
10. 3. The combination with fence posts adapted to receive panels on their sides, removable by lifting upward, of pieces mounted on the posts, extending laterally therefrom over the panels and meeting between the posts, forming a top rail for the fence; and means fastening removably said pieces comprising the top rail to the posts.
- Signed by me at Boston, Mass., this 2nd day of November, 1911.

JOHN R. POTTERTON.
